CLAIM

The ornamental design for a combination handset and
speaker dialer telephone stand unit, as shown and de-
scribed.

DESCRIPTION

FIG. 1 is a top plan view of a combination handset and
speaker dialer telephone stand unit showing our new
design;

FIGS. 2 and 3 are respectively front and rear eleva-
tional views thereof;

FIG. 4 is a bottom plan view thereof;

FIGS. 5 and 6 are respectively right and left side eleva-
tional views thereof;

FIG. 7 is a front, top and right side perspective view of
the telephone unit in cradled relationship; and

FIG. 8 is a top plan view of the handset, and the stand,
shown independently, spaced apart from each other.

FIG. 1
